UNITED STATES PATENT OFFICE.

WILLIAM H. COBB, OF SHARON HILL, PENNSYLVANIA.

SHOW-CASE.

1,075,334.

Specification of Letters Patent.

Patented Oct. 14, 1913.

Application filed April 16, 1913. Serial No. 761,410.

To all whom it may concern:

Be it known that I, WILLIAM H. COBB, a citizen of the United States, residing at Sharon Hill, in the county of Delaware and State of Pennsylvania, have invented certain new and useful Improvements in Show-Cases, of which the following is a specification.

My invention relates to show cases, and it 10 has particular relation to the construction and arrangement of the rear door for permitting access to the interior of the case, which door provides means for protecting the contents from dust, flies and the like 15 during the periods when access to the contents is not desired.

The principal object of my invention is to provide a simple and inexpensive form of door for show cases which may be readily 20 manufactured in various sizes, and which, when in use, may be manipulated quickly and easily without binding.

In my previous Letters Patent of the United States No. 1,044,749, dated Nov. 19, 25 1912, I have shown a form of sectional show case or counter guard particularly adapted for use in 5 and 10¢ stores, and in department stores, in which glass panels on the top and front side were provided for protecting the materials displayed on the counter top and which was open in the rear for ready and convenient access by the attendant. I have found that in some instances it is desirable that means be provided for 30 closing the rear open space during the periods when access to the interior of the case is not required, and my invention therefore contemplates a form of door for closing this rear open space, but which form of door 35 however is adaptable as well to other types of show cases.

The nature and characteristic features of my invention will be more readily understood from the following description taken 45 in connection with the accompanying drawings forming part hereof, in which—

Figure 1 is a perspective view, looking from the rear, of a portion of a show case provided with a door for closing the rear 50 and embodying the main features of my present invention; Fig. 2 is a transverse section of the structure shown in Fig. 1; and

Figs. 3 and 4 are detail sectional views taken approximately on the line $\alpha-\alpha$ of Fig. 2, at the intermediate and end frames respectively 55 of the show case proper, and illustrating the arrangement of means for guiding and supporting the door in its open position.

Referring to the drawings, in the particular embodiment of my invention therein 60 shown, 10 is a store counter, of any preferred construction, to the edges of the top board 11 of which are secured the rails 12 and 13 forming ledges for the retention of the articles placed upon the counter. 65

14 is the end support or frame and 15 is one of the intermediate supports or frames of the show case proper, each of which supports or frames consists of a horizontal top portion 16, an inclined front leg 17 and an 70 inclined rear leg 18. Adjustably secured to the rear leg 18 is a foot bar 19 having a horizontal lug portion 20 for securing the member 19 to the rear portion of the counter. The lower or extreme end of the inclined 75 front leg 17 of each of the frames 14 and 15 may be provided with a vertical lug portion 21, or other suitable means for securing said leg to the counter or the front rail 13 thereof may be provided. The foot member 19 as before stated is adjustably secured to the inclined rear leg 18 for the purpose of adjusting the frames, which are usually made in stock sizes, to varying inclinations 80 of the top surface of the counter. 85

The horizontal portion 16 and the front inclined leg 17 of the frame 14 or 15 serves respectively for the support of horizontal panels 24 and inclined panels 25, of glass, which serve to guard and protect the articles 90 which are placed upon the counter top from contamination by dust, flies and other objectionable things.

The glass panels 24 and 25 are secured to the frames 14 and 15 in any suitable manner, such for example as is described in detail in my previous Letters Patent No. 1,044,749 hereinbefore referred to. There is also described and shown in said patent 95 means for preventing longitudinal separation of the glass panels from the frames, as well as for stiffening the structure generally, comprising a series of horizontally extending tie rods 36 which are secured to the 100

rear inclined legs 18 near the top thereof in a suitable manner as particularly described in said Letters Patent.

The door forming the principal novel part 5 of my present invention comprises a plate 50, preferably made of thin sheet metal and having secured thereto, near the top and bottom, longitudinally extending bars 51 which serve to stiffen the plate 50 and thereby permit the same to be made of thinner material while preserving the necessary 10 rigidity and shape. Mounted in the bars 51 preferably near the ends thereof are transversely extending rods 52 maintained a short 15 distance above the plate 50 by means of short angular extensions 53, each of said rods 52 extending from one of the longitudinal bars 51 to the other of said bars, as clearly shown in Figs. 1 and 2 of the drawings. 20 The rods 52 are so located as to include the tie rods 36 between said rods 52 and the plate 50 of the door, the said tie rods 36 thereby serving in conjunction with the rods 52 as a support for the door as well as a 25 guide for the proper location thereof in its closed position and also during its operation to the open position.

The rods 52 on account of their arrangement and extension above the surface of the 30 plate 50 also serves as handles for the convenient manipulation of the door. To further insure the proper guiding of the door to its open position there are provided adjacent each end of said door and secured 35 to the frames 14 and 15 horizontally mounted bars 54 preferably angle shaped in cross-section, and having up-turned lips 55 at their inner or front ends which serve as stops to limit the movement of the door at 40 the final open position.

In order to cause all the doors in a series 45 of sections of a show case to rest in the same location with respect to the frames and thereby present a neat and uniform appearance, each foot member 19 is provided with a stop member comprising a short bar 56 extending beyond the side margins of said foot member to form an abutment against which the door will rest in its closed 50 position. The projecting portions of the bar 56 are preferably provided with a covering 57 of rubber or the like to eliminate to some extent the noise and jar which would otherwise occur when the door is closed.

55 It will thus be seen that there is provided a simple and efficient form of door for closing the rear portion of show cases or counter guards which may be inexpensively constructed and which is so arranged 60 that it can be manipulated readily and easily.

It will of course be understood that while the door as herein described is particularly adaptable for use in connection with the 65 show case described and shown in my previ-

ous Letters Patent No. 1,044,749, it can however be used with other types of show cases or counter guards.

Having thus described the nature and characteristic features of my invention what 70 I claim as new and desire to secure by Letters Patent is: —

1. In a show case or counter guard, a door comprising a plate, rods supported from said plate and extending a short distance above 75 the surface thereof, and means carried by a stationary portion of the structure engaged by said rods to form a guide and support for the door.

2. In a show case or counter guard, a door 80 comprising a plate, stiffening bars secured to said plate and extending longitudinally thereon, rods mounted in said stiffening bars and extending transversely a short distance above the surface of the plate, and means 85 carried by a stationary portion of the structure engaged by said rods to form a guide and support for the door.

3. A show case or counter guard comprising 90 a series of spaced frames, glass panels mounted on the top and one side of said frames, and a door for closing the other side comprising a plate, rods supported from said plate and extending above the surface thereof a short distance therefrom, and a 95 member secured to said frames and engaged by said rods to form a guide and support for the door.

4. A show case or counter guard comprising 100 a series of spaced frames, glass panels mounted on the top and one side of said frames, tie rods extending between said frames and secured thereto near the top thereof, and a door for closing the other side of the structure comprising a plate, rods supported from said plate and extending above the surface thereof a short distance therefrom, said rods engaging the tie rods to 105 form a guide and support for the door.

5. A show case or counter guard comprising 110 a series of spaced frames, glass panels mounted on the top and one side of said frames, and a door for closing the other side comprising a plate, rods supported from said plate and extending above the surface 115 thereof a short distance therefrom, a member secured to said frames and engaged by said rods to form a guide and support for the door, and an additional guide and support for the door comprising horizontally 120 extending bars secured to the inner portions of the frames near the top thereof.

6. A show case or counter guard comprising 125 a series of spaced frames, glass panels mounted on the top and one side of said frames, and a door for closing the other side comprising a plate, rods supported from said plate and extending above the surface thereof a short distance therefrom, a member secured to said frames and engaged by 130

said rods to form a guide and support for the door, and an additional guide and support for the door comprising horizontally extending bars secured to the inner portions of the frames near the top thereof, said bars having stops at their front ends to limit the final open position of the door.

In testimony whereof, I have hereunto signed my name in the presence of two witnesses.

WILLIAM H. COBB.
